MAGNETIC SOUND POD

Samuel I. Berger

Application July 9, 1953

9 Claims. (C)

This invention relates to telephones and more particularly to a telephonic unit of the self-energizing type that is adapted to be used either for transmitting or receiving sound.

It is among the objects of the invention to provide a telephonic unit of the above type which is efficient in operation and provides a relatively high-fidelity response, yet is simple and compact in construction, light in weight, having but few relatively inexpensive parts that are not likely to become deranged and which are designed to facilitate mass production assembly to form the complete unit at relatively low cost.

the complete unit at relatively low cost.

According to the invention, these objects are accomplished by the arrangement and combination of elements hereinafter described and particularly recited in the claims.

In the accompanying drawings in which is shown one or more of various possible embodiments of the several features of the invention,

Fig. 1 is a longitudinal sectional view of the unit,

Fig. 2 is a transverse sectional view thereof taken along line 2—2 of Fig. 1, and Fig. 3 is a plan view taken along line 3—3 of Fig. 1.

Referring now to the drawings, the telephonic unit desirably comprises a substantially rectangular base plate 11 of any suitable non-magnetic material such as brass, copper or plastic, the base plate 11 being of copper in the illustrative embodiment herein shown.

The base plate 11 adjacent the edge 12 thereof desirably has a plurality of outstanding lugs 13, 14 and 15 integral therewith and preferably struck out therefrom between which is positioned one end of a substantially L-shaped pole piece 16 of magnetic material such as steel. As shown in Fig. 1, the lugs 14 and 15 straddle the sides of leg 17 of the pole piece 16 and the lug 13 is against the end edge thereof, said lugs being of such length as to rise above the top surface of said leg 17.

In order that the pole piece 16 may be properly positioned on the base plate 11 and restrained from longitudinal or transverse movement with respect thereto, the undersurface of leg 17 of the pole piece 16 desirably has a pair of bosses 18 protruding therefrom which may be positioned in complementary openings 19 in the base plate 11.

As shown in Fig. 1, a pair of spaced parallel brackets 21 and 22, also of non-magnetic material such as copper, are mounted on the base plate 11 extending transversely across the leg 11

92,918 **POWERED TELEPHONE** **1952, Serial No. 297,843**
CH. 170 - 108

(Cl. 179—102) **2** of pole piece 16, one of said brackets, i. e., bracket 24 being against the unturned end 22 of said bracket.

5 of pole piece 16, one of said brackets, i. e., bracket 21 being against the upturned leg 23 of said pole piece 16. Although the brackets 21 and 22 may be mounted in any suitable manner, in the illustrative embodiment herein shown, each bracket has a rectangular cutout 24 at its bottom edge defining a pair of legs 25 which straddle the pole piece 16 and extend respectively through pairs of transversely aligned openings 26 on each side thereof, the brackets being secured in place as by twisting the ends of legs 25 which protrude beneath said base plate 11.

10 Positioned between the brackets 21 and 22 is a coil of wire 29 which is desirably wound around a tubular core 31 of insulating material desirably substantially rectangular in cross section. The core 31 desirably has a substantially rectangular plate 32 of insulating material at each end thereof with a rectangular slot therein in which the respective ends of the core may be affixed, the end plates desirably fitting snugly against the associated brackets 21 and 22.

15

20

25 Each of the brackets has a slot 34 therethrough which are longitudinally aligned with respect to the leg 17 of pole piece 16. Affixed as by soldering in the slot 34 in bracket 22 is one end of an armature reed 35 of magnetic material preferably of steel which is centrally positioned in and extends through the core 31 and through the slot 34 in bracket 21 and protrudes as at 36 past the upturned leg 23 of pole piece 16, said reed 35 being slightly spaced from said leg 23 to define an air gap therebetween.

35 Positioned between the lugs 13, 14 and 15 and straddled thereby is a rectangular block magnet 38 preferably of "Alnico" having its north pole, for example, resting on the end of leg 17 of pole piece 16. Positioned against the other or south pole of magnet 38 is the end of the leg 39 of a second substantially L-shaped pole piece 40 which extends parallel to the leg 17 of pole piece 16 and has a downwardly extending leg 41 which is aligned with leg 23 of pole piece 16 and is also spaced from the protruding end 36 of armature reed 35 defining a second air gap therebetween, said end 36 being centrally positioned between said legs 23 and 41. The pole piece 40 which rests on the upper edges of brackets 21 and 22 being positioned in longitudinally aligned notches 45 therein is securely retained in position by means of lugs 46 formed integral with the brackets 21 and 22, which extend through complementary longitudinally aligned openings 47 in pole piece 39 and are bent over as at 48.

With the construction above described, the

lugs 13, 14 and 15 will prevent longitudinal or transverse displacement of the block magnet 38 and the pole piece 40 which is securely clamped in place against the brackets 21, 22 will prevent vertical displacement of said block magnet 38.

The base plate 11 is desirably mounted on a panel 51 which carries a flexible diaphragm 53. Although the base plate 11 may be mounted in any suitable manner, in the embodiment herein shown, the panel 51 which preferably is of plastic has four outstanding studs 54 desirably arranged in a rectangle and tapering slightly toward the nose 55 thereof. The studs 54 are designed to fit into complementary openings 56 near each corner of the rectangular base plate 11 and the plate is affixed to the panel as by applying heat to the nose end 55 of the studs, the plate 11 thereby wedging on the tapering portion thereof.

The panel 51 on the outer surface thereof desirably has a circular cavity 58 with a central opening 60 in the floor 59 thereof through which extends a drive rod 61 affixed at one end as by soldering to the protruding end 36 of the armature reed 35. The other end of the drive rod 61 is affixed, also as by soldering, to diaphragm 53 which desirably is of metal and which is positioned at its periphery on an annular shoulder 62 formed about the periphery of said circular cavity 58. Although the diaphragm 53 may be retained on said shoulder in any suitable manner, in the embodiment herein shown, an annular member 63 of outer diameter substantially equal to that of the circular cavity 58 is positioned in the latter and desirably cemented therein, the rim of said annular member clamping the periphery of said diaphragm 53 against said shoulder 62. Desirably a perforated disk 65 is affixed as by cementing to an inturned flange 66 of annular member 63, said disk and said annular member functioning as the mouth piece and receiver of the telephonic unit.

When the telephonic unit is used as a receiver and a signal current is applied to the ends of coil 29 from the output of the coil of an identical unit (not shown), a force will be created to vibrate the armature reed 35 thereby decreasing one of the air gaps between legs 23, 41 and armature reed 35, and increasing the other. Such movement of the armature reed will, through drive rod 61, effect movement of the diaphragm 53 to produce an audible sound corresponding to that applied to the mouth piece of said other identical unit.

When the unit is used as a microphone or transmitter, the diaphragm 53 will be vibrated by the sounds impressed thereon and such vibration will be transmitted through drive rod 61 to armature reed 35. The movement of the armature reed 35 will generate a signal voltage in the coil 29 which will be transmitted through suitable leads to the coil of the companion unit.

With the construction above described, a simple yet highly efficient telephonic unit is provided, which may readily be assembled by mass production methods and which is neat and compact and may be used without need for any batteries when transmission of intelligence is desired for a short distance.

As many changes could be made in the above construction, and many apparently widely different embodiments of this invention could be made without departing from the scope of the claims, it is intended that all matter contained in the above description or shown in the accom-

panying drawings shall be interpreted as illustrative and not in a limiting sense.

Having thus described my invention, what I claim as new and desire to secure by Letters Patent of the United States is:

1. A telephonic unit comprising a block of permanent magnet material, a pair of pole pieces each having one end against one of the respective poles of said magnet and extending in parallel paths away therefrom, said pole pieces having their other ends bent toward each other defining a gap therebetween, a pair of spaced parallel brackets extending transversely between said pole pieces, an armature strip affixed at one end to the bracket adjacent said magnet block and extending away therefrom parallel to said pole pieces past the other bracket and through the gap between the bent ends of the pole pieces, a coil surrounding said armature and positioned between said brackets, a diaphragm, a support for said diaphragm and a drive rod connecting said diaphragm to the free end of said armature.

2. A telephonic unit comprising a base plate of non-magnetic material, a substantially L-shaped pole piece on said base plate having one leg seated thereon and one leg bent outwardly therefrom at right angles thereto, a block of permanent magnet material having one pole positioned on the free end of the leg of the pole piece on said base plate, a second substantially L-shaped pole piece having the free end of one leg thereof on the other pole of the magnet and having an inwardly bent leg aligned with the outwardly bent leg of the first pole piece and spaced therefrom defining a gap therebetween, a pair of spaced parallel brackets extending transversely between said pole pieces and affixed to said base plate, an armature strip affixed at one end to the bracket adjacent said magnet block and extending away therefrom parallel to said pole pieces past the other bracket and through the gap between the bent ends of the pole pieces, a coil surrounding said armature and positioned between said brackets, a diaphragm, a support for said diaphragm and a drive rod connecting said diaphragm to the free end of said armature.

3. The combination set forth in claim 2 in which said base plate has a plurality of lugs rising therefrom and straddling the free end of the leg of the pole piece on said base plate.

4. The combination set forth in claim 2 in which said base plate has a plurality of lugs rising therefrom and straddling the free end of the leg of the pole piece on said base plate, said lugs extending beyond the upper surface of said leg, said magnet block being positioned between said extending portions of said lugs.

5. The combination set forth in claim 2 in which said base plate has a plurality of lugs rising therefrom and straddling the free end of the leg of the pole piece on said base plate, said base plate and said leg having complementary coacting conformations to restrict longitudinal and transverse movement of said pole piece on said base plate.

6. The combination set forth in claim 2 in which said base plate has a plurality of lugs rising therefrom and straddling the free end of the leg of the pole piece on said base plate and said leg has a plurality of bosses on the undersurface thereof which coact with complementary openings in said base plate to restrict longitudinal and transverse movement of said pole piece on said base plate.

7. A telephonic unit comprising a base plate

of non-magnetic material, a substantially L-shaped pole piece on said base plate having one leg seated thereon and one leg bent outwardly therefrom at right angles thereto, a block of permanent magnet material having one pole positioned on the free end of the leg of the pole piece on said base plate, a plurality of lugs rising from said base plate and straddling the free end of the leg of the pole piece on said base plate and the block magnet thereon, a pair of spaced parallel brackets extending transversely across the leg of said pole piece and affixed to said base plate, a second substantially L-shaped pole piece having the free end of one leg thereof on the other pole of said block magnet and extending across the upper edges of said brackets, and having an inwardly bent leg aligned with the outwardly bent leg of the first pole piece and spaced therefrom defining a gap therebetween, complementary means on the upper edges of said brackets and the leg of said second pole piece extending thereacross securely to retain said leg on said upper edges, thereby retaining said block magnet between said lugs, an armature strip affixed at one end to the bracket adjacent said magnet block and extending away therefrom parallel to said pole pieces past the other bracket and through the gap between the bent ends of the pole pieces, a coil surrounding said armature and positioned between said brackets, a diaphragm, a support 30

for said diaphragm and a drive rod connecting said diaphragm to the free end of said armature.

8. The combination set forth in claim 7 in which the support for said diaphragm comprises a panel having a circular cavity in the front face thereof with an annular shoulder on which the periphery of the diaphragm is seated, means clamping said diaphragm on said shoulder supporting means on the rear face of said panel for said base plate, said cavity having an opening in the floor thereof through which said drive rod extends.

9. The combination set forth in claim 7 in which the means to retain the leg of the pole piece on the upper edges of said bracket comprises a lug formed integral with each of said edges and extending through complementary openings in said leg.
